(57) **CLAIM**

The ornamental design for a stretch band, as shown and described.

DESCRIPTION

FIG. 1 is a perspective view of a stretch band showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view of the stretch band showing a state of use thereof.

The broken line showing of the two hands in FIG. 8 depicts environment and forms no part of the claim.
